UNITED STATES PATENT OFFICE.

WILLIAM WHITE, OF NEW YORK, N. Y., ASSIGNOR TO CLARENCE WHITMAN & CO., OF SAME PLACE.

DESIGN FOR A BEDSPREAD.

SPECIFICATION forming part of Design No. 23,490, dated July 24, 1894.

Application filed June 26, 1894. Serial No. 515,792. Term of patent 3½ years.

To all whom it may concern:

Be it known that I, WILLIAM WHITE, a citizen of the United States, residing in the city, county, and State of New York, have invented and produced a new and original Design for Bedspreads, of which the following is a specification, reference being had to the accompanying drawing, which represents a face view of a portion of a bedspread embodying my design, part only being shown in detail, the remainder being shown in outline.

The essential feature of my design is a bedspread ornamented with a series of rectangles inclosing stars, and with an ornamental border consisting of a series of rectangles with adjacent prismatic ornaments.

In the drawing *a a* are series of rectangles within which are the stars *b b* and the filled-in configuration of a check effect *c*; the field *d* of the spread between the rectangles being

filled in with a configuration *d* representing a lattice effect. The border consists of a series of filled-in rectangles *e e* with interposed prismatic ornaments *f*. Adjoining the border is an inner border *g* exhibiting a check effect. Forming part also of the field are the converging bands *j, k*, the zig-zag bands *l m n*, the intervening spaces of the field being filled in by check and lattice effect configurations *o* and *p* respectively, and the shaded and lattice effect configurations *r s* respectively.

What I claim is—

The design for a bed-spread, substantially as shown and described.

WILLIAM WHITE.
